J. N. REYNOLDS.
TELEPHONE SWITCH MECHANISM.
APPLICATION FILED MAY 22, 1916.

1,215,860.

Patented Feb. 13, 1917.

Inventor:
John N. Reynolds.
John C. Kennedy, Atty.

UNITED STATES PATENT OFFICE.

JOHN NEWBERRY REYNOLDS, OF GREENWICH, CONNECTICUT, ASSIGNOR TO WESTERN ELECTRIC COMPANY, INCORPORATED, OF NEW YORK, N. Y., A CORPORATION OF NEW YORK.

TELEPHONE SWITCH MECHANISM.

1,215,860.

Specification of Letters Patent. Patented Feb. 13, 1917.

Application filed May 22, 1916. Serial No. 99,116.

To all whom it may concern:

Be it known that I, JOHN NEWBERRY REYNOLDS, a citizen of the United States, residing at Greenwich, in the county of Fairfield and State of Connecticut, have invented certain new and useful improvements in Telephone Switch Mechanisms, of which the following is a full, clear, concise, and exact description.

10 This invention relates to a telephone switch mechanism and more particularly to improvements in switch mechanisms such as shown in Patent No. 1,181,734 of March 16, 1915, in which circuit connections are established through the agency of two sets of relatively movable contact members carried by movable bars hereinafter termed trunk and line bars. The trunk bars are adapted to be selectively displaced to bring their 20 contacts into position to be engaged by contacts upon a line bar, the engagement between contacts of an operated line bar and trunk bar causing said trunk bar to be swung to a position where the contacts will 25 be out of line of engagement with the contacts of subsequently operated line bars. In the switch shown in the Patent 1,181,734 there is an individual latching means for each trunk bar controlled by a common operating means for causing a preselective operation of the trunk bars and individual releasing magnets for restoring the trunk bar when taken for use.

30 The object of this invention in general is to provide certain improvements in a switch structure of the type shown in the Patent 1,181,734 whereby parts of the operating mechanism may be easily removed and replaced in case of trouble.

40 According to the features of this invention, individual operating and releasing magnets are provided for the trunk bars. The operating and releasing magnets individual to each bar are mounted upon a bracket member which is adapted to be removably secured to the supporting frame of the switch.

50 The drawing is a perspective, with parts broken away, of a switch embodying the features of this invention.

As shown in the drawings, 2 and 3 designate end frame members, and 4 and 5 top and bottom frame members, respectively. Pivotally supported in the end members 2 55 and 3 are line bars 6, 6 each provided with

a plurality of sets of contacts 7, 7. Pivotally supported in the top and bottom frame members 4 and 5 are trunk bars 8, 8 each having a plurality of sets of contacts 9, 9. Each line bar 6 is adapted to be moved longitudinally by means of a magnet 10 and through a slight angle by means of a cam projection 11 in the end frame member 3 which is engaged by a projection 12 carried by the bar 6. Each trunk bar 8 has secured to it a latch member 15 adapted to be engaged by the armature 16 of an operating magnet 17 to rotate the trunk bar 8 into a displaced position, where it is in position to have its contacts 9 engaged by contacts 7 of an operated line bar. The latch member 15 is provided with a projection 20 adapted when the trunk bar is displaced to be engaged by a holding catch 21 carried by an armature 22 of a release magnet 23. The energization of the release magnet 23 disengages the catch 21 from the projection 20 and permits the trunk bar 8 to be moved from its displaced position by means of a spring 25. The armature 22 of the release magnet 23 is normally held in latched position by means of a spring 35.

55 The operating and release magnets 17 and 23 and their associated mechanism for co-operating with a latch member 15 are mounted upon a bracket member 30 which is removably secured to a projection 31 formed upon the lower frame member 5. The bracket 30 may be secured to the projection 31 by means of screws 32, 32, thus making 60 of the operating and release magnets a unitary structure, which may be easily removed and replaced in case of trouble.

What is claimed is:

1. In a switching device, a plurality of 65 trunk bars, contacts on the trunk bars, line bars, contacts on the line bars adapted to engage the contacts on the trunk bars, an individual magnet for moving each of the trunk bars into a displaced position for engagement between the contacts of line and trunk bars, latching means individual to each of said trunk bars for holding them in a displaced position, and an individual release magnet for each of said latching 70 means.

2. In a switching device, a plurality of 75 trunk bars, contacts on the trunk bars, line bars, contacts on the line bars adapted to engage the contacts on the trunk bars, a 80

frame supporting the trunk and line bars, an individual operating electromagnet for moving each of the trunk bars into displaced position for engagement between the contacts of line and trunk bars, latching means for holding each of said trunk bars in displaced position, a magnet individual to each of said trunk bars for causing the release thereof, and means for removably supporting said operating and releasing electromagnets on said frame.

3. In a switching device, a plurality of line bars, contacts on the line bars, trunk bars, contacts on the trunk bars, said trunk

bars being adapted to be moved into a displaced position to have their contacts engaged by the contacts on said line bars, an electromagnet for moving each of said trunk bars into a displaced position, a latch for each of said trunk bars, a release magnet for controlling each of said latches, a frame in which said bars are supported, and a removable bracket carried by said frame upon which the operating and release magnets individual to a trunk bar are mounted. 25

In witness whereof, I hereunto subscribe my name this 18th day of May A. D., 1916.

JOHN NEWBERRY REYNOLDS.
